TOY FIGURE

Peter Rauls, Muhlhausen, Germany, assignor to Iris Produktions- und Vertriebsgesellschaft von Schmuckkarten und kunstgewerblichen Artikeln m.b.H., Frankfurt am Main, Germany

Filed Jan. 21, 1969, Ser. No. 15,546

Term of patent 14 years

Int. Cl. D21—02

U.S. Cl. D34—2

FIG.1

FIG.3

FIG.2

FIG.5

FIG.4

FIG. 1 is a front elevational view of a fur-covered toy figure showing my new design;

FIG. 2 is a rear elevational view thereof;

FIG. 3 is an elevational view taken from either side thereof;

FIG. 4 is a bottom plan view thereof;

FIG. 5 is a top plan view thereof.

I claim:

The ornamental design for a toy figure, as shown and described.
